BUFFING WHEEL

John J. Lawler, Chicago, Ill., assignor to Ajax Buff Company, Chicago, Ill., a corporation

Application February 8, 1950, Serial No. 143,047

5 Claims. (Cl. 51—193)

1

The present invention relates to a buffing wheel and more particularly to a buffing wheel in which a cloth buff is secured to a hub assembly adapted to be rotatably disposed on a shaft, the hub assembly carrying fluid directing means for circulating a coolant fluid in heat transfer relation with the buff as the wheel is rotated.

Conventional cloth buffing wheels comprise generally an annular cloth buff secured to a hub assembly by means of which the buff may be rotatably disposed upon the spindle or shaft. In use, a plurality of such buffs are generally secured to a spindle or shaft in axial alignment with the peripheral surfaces of the buffs forming a cylindrical buffing surface against which a work piece may be held. Due to friction between the work piece and the buff and internally of the buff, considerable heat evolved during use of the buffing assembly and this heat may become great enough to cause burning or charring of the buffs of the assembly.

The present invention now provides an improved buffing wheel in which the wheel hub carries means for directing air radially through the wheel. In addition, each wheel is provided with means spacing it from an adjacent wheel of the assembly so that radial fluid flow passages exist between the adjacent buffs for the flow of coolant through the assembly.

In ordinary use in a buffing assembly, the coolant fluid is air and the vertical convection currents, resulting from the evolution of heat at the peripheral working surface and within the assembly itself, cause a draft of air vertically through the assembly, or more particularly through the air flow passages provided between adjacent buffs by the hub spacing means. The air directing means carried by the hub also aid in the flow of currents through the assembly, thus increasing the heat dissipation efficiency thereof.

It has been found that the buff ventilating and cooling means of the present invention greatly extends the permissible range of rotational speeds without burning or charring of the buff, and also that an unlimited number of buffing wheels may be positioned upon a spindle or shaft to form an efficient, well ventilated assembly.

It is, therefore, an important object of the present invention to provide an improved buffing wheel having coolant circulating means and radial heat dissipating channels associated therewith for preventing burning or charring of the buffing elements.

Another important object of the present in-

vention is to provide an improved buffing wheel having an annular cloth buff secured to a hub assembly provided with coolant circulating means for directing a coolant fluid through the buff.

It is a further important object of the present invention to provide an improved buffing wheel assembly including a plurality of annular buffs each secured to a hub carrying coolant circulating means for directing coolant fluid radially outwardly through the buff and also providing radial flow passages communicating with the buff for receiving coolant fluid from the hub.

Other and further important objects of this invention will be apparent from the disclosures in the specification and the accompanying drawings.

On the drawings:

Figure 1 is a fragmentary elevational view of a buffing wheel of the present invention;

Figure 2 is a sectional view, with parts shown in elevation, illustrating a buffing assembly composed of a plurality of buffing wheels similar to that of Figure 1;

Figure 3 is an elevational view of a hub element of the wheel of Figure 1 provided with coolant circulating means;

Figure 4 is a sectional view taken along the plane IV—IV of Figure 3;

Figure 5 is an exploded sectional view illustrating the assembly of the buffing wheel of the present invention;

Figure 6 is a fragmentary sectional view of an assembled buffing wheel of the present invention;

Figure 7 is a side elevational view, similar to Figure 1, illustrating a modified form of a buffing wheel;

Figure 8 is a sectional view, taken on the plane VIII—VIII of Figure 7; and

Figure 9 is a side elevational view of a modified form of a clamping element employed in the wheel of Figure 7.

As shown on the drawings:

In Figure 1, reference numeral 10 refers generally to a buffing wheel of the present invention including an annular cloth buff 11 and a hub assembly 12 secured to the buff 11.

The annular buff 11 may be any of the numerous types of annular buffing cloth constructions known in the art. However, it is preferred that annular buffs formed of a plurality of elongated bias-cut strips be employed. Such buffs are generally prepared by transversely gathering or pleating a plurality of superimposed strips, sewing the strips longitudinally down the center,

as at 11a in Figures 5 and 6, and then doubling the strip upon itself along the sewed line 11a. The double strip is then folded or pleated into an annular configuration having a smooth generally rounded inner periphery 11b, and the completed buff is preferably sewed, as at 11c adjacent its inner periphery.

The hub assembly 12 includes a circular disk 13 and an annular ring 14 secured to opposing sides of the buff 11 adjacent the inner periphery 11b thereof. The disk 13 is generally circular in outline and is provided with a centrally located, integrally formed, cylindrical flange 15 defining an aperture 16 concentric with the disk (Figures 3 and 4).

That portion of the disk 13 surrounding the flange 15 is provided with a plurality of elongated, radially extending reinforcing ribs 17 symmetrically disposed about the flange 15. Air pumping means are provided, as will be hereininafter described, by a plurality of air directing fins 18 defined by substantially semi-circular, arcuate slits 19 formed intermediate adjacent strengthening ribs 17, with that portion of the disk outlined by the slits 19 being deformed from the plane of the disk in that direction in which the flange 15 extends from the plane of the disk.

A plurality of peripherally spaced, radially extending teeth 20 are formed integrally with the disks 12, the teeth having tapered outer portions 21 for a purpose to be hereininafter described. The teeth 20, prior to assembly of the buffering wheel 10, are bent or deformed to lie in a plane substantially normal to the plane of the disk, as shown in Figure 5.

The annular ring 14 is of slightly smaller outside diameter than the outside diameter of the disk 13 and is of approximately the same inside diameter as the annular buff 11. The ring 13 is provided with a plurality of circumferentially spaced apertures 22, corresponding in location and approximate size to the teeth 20, when the latter are deformed as in Figure 5.

Assembly of the wheel 10 is shown in Figures 5 and 6 and includes as a first step the positioning of the disk 13 and the ring 14 on the opposing sides of the annular buff 11. Next, the terminal portions 21 of the teeth 20 are forced through the buff adjacent the inner periphery 11b thereof to project outwardly beyond the buff 11 and through the apertures 22 of the ring 14. The terminal portions 21 of the teeth 20 are then deformed radially inwardly of the ring 14 to overlie the exposed outer surface of the ring and to clinch the buff 11, the disk 13 and the ring 14 into a rigid assembly.

It will be noted from Figures 2, 5 and 6 that the fluid directing fins 18 extend inwardly of the assembly to underlie the inner periphery 11b of the buff in closely spaced relation thereto.

In the modified form of wheel illustrated in Figures 7-9, inclusive, a circular disk 35, similar to the disk 13 of Figure 1 and provided with peripheral teeth 20, carries elongated, generally oval air directing fins 36. The fins 36 are circumferentially spaced about the axial aperture 16 of the disk and extend radially across the inner portions of the disk 35. The fins are deformed from the plane of the disk to lie at an angle thereto so that effective air direction may be obtained.

The modified form of ring 37 is provided with circumferentially spaced apertures 38 corresponding to the apertures 22 of the rings 14 of the embodiment of Figures 1-6, inclusive. Those

portions 39 of the ring immediately contiguous to and radially inward from the apertures 38 are deformed from the plane of the ring to provide local embossments having plane upper surfaces for receiving the teeth portions 21 thereagainst in extended surface engagement when the wheel is assembled as in Figure 8.

It will be seen that, in the assembled wheel, the embossments 39 and the teeth portions 21 extend beyond the plane of the ring 37 for a distance equal to the thickness of the tooth portion and the offset height of the embossment 39. The radial air flow channels between the teeth and embossments are of the same height even after positioning of the wheel in an assembled as in Figure 2.

As shown in Figure 2, a plurality of the wheels 10, assembled as hereinbefore described, are preferably secured to a rotatable shaft 24 to form a complete buffering assembly. The shaft 24 is provided with an enlarged, radially outwardly extending shoulder 25 against which the mounting plate 26 is bottomed. The plate 26 is of approximately the same diameter as the ring 14 and is provided with a central embossment 28 having an inner bore 29 snugly receiving the shaft 24. Next, a wheel 10 is positioned on the shaft 24 with the terminal end of the flange 15 being bottomed upon the corresponding terminal end of the embossment 28 and the terminal portion 21 of the teeth 20 abutting the plate 26 adjacent its outer periphery. Next the remaining wheels of the assembly are telescoped over the shaft 24, followed by a second clamping plate 30 snugly receiving the shaft 24. The assembly is secured to the shaft 24 by means of a nut 32 threaded upon the exteriorly threaded terminal portion 33 of the shaft 24.

It is to be noted that the wheels 10 are spaced from one another by the abutment of the terminal ends 21 of the teeth 20 against the disk 13 of the adjacent wheel 10 and that radial air passages are provided between adjacent wheels 10 by the spaces between the teeth 20. In the second embodiment of the invention, as illustrated in Figures 7-9, the depth of the radial passages is increased by the provision of the offset portions 39 to increase correspondingly the radial flow of air. The radial passages accommodate the vertical flow of convection currents through the wheel assembly, thus increasing the heat dissipation efficiency of the assembly. The fins 18 thrust air radially outwardly through the radial air passages defined by the teeth to exert a cooling effect upon the buffs 11, thereby obviating the possibility of the buffs becoming overheated and eventually charred or burned during employment of the assembly.

It will be understood that modifications and variations may be effected without departing from the scope of the novel concepts of the present invention.

I claim as my invention:

1. A buffering wheel comprising an annular cloth buff, a circular disk abutting one side surface of said buff, teeth formed integrally with said disk and extending through said buff, an annular ring 70 abutting the opposing side surface of said buff and having peripheral apertures formed therein to receive said teeth, said teeth being deformed radially into extended surface engagement with said ring to secure said disk and ring to said buff, said teeth extending axially beyond said ring to

space said wheel from an adjacent wheel of a buffing assembly, and air directing vanes struck from said disk and extending generally perpendicularly with respect to the axis of rotation and at acute angles to the plane of rotation of said wheel to underlie said buff, said vanes serving to direct air radially outwardly through channels defined by said teeth spacing said wheel from an adjacent wheel into contact with said buff to cool the same and to prevent overheating thereof.

2. A buffing wheel comprising a cloth buff, a circular disk having peripherally spaced teeth formed integrally therewith extending through said buff in a plane approximately normal to the plane of said disk, an annular ring for abutting an opposing surface of said buff and having apertures therein for receiving said teeth extending through said buff, said ring having peripherally spaced protuberances extending axially of the ring away from said buff and said teeth being deformed radially of said ring to lie against the exposed surfaces of said protuberances to clamp said disk and said ring to said buff, said protuberances and said teeth lying thereagainst forming radial cooling air channels, and radially extending air directing vanes struck from said disk and extending axially inwardly therefrom to underlie said buff for directing air radially outwardly through said channels and past the buff to prevent overheating of the same.

3. A buffing assembly comprising a plurality of buffing wheels, each of said wheels including an annular cloth buff, clamping elements abutting opposing side surfaces of said buff adjacent the inner periphery thereof, means extending from one of said clamping members through said buff into extended surface engagement with the other of said clamping members to secure said members to said buff and to space the associated buff from adjacent buffs of said assembly, additional spacing means formed integrally with one of said clamping elements and contacting said first mentioned means for increasing the spacing between adjacent buffs to form radial cooling air channels, and air directing vanes formed integrally with one of said clamping members and extending axially of said assembly at an acute angle thereto for directing air radially outwardly therefrom through said channels and between said buffs to prevent overheating of the same.

4. A buffing wheel comprising an annular cloth buff, a circular disk abutting one side surface of said buff, teeth formed integrally with said disk and extending through said buff, an annular ring abutting the opposing side surface of said buff

and having peripheral apertures formed therein to receive said teeth, said ring having portions immediately contiguous to and radially inward from each of said apertures locally deformed from the plane of the ring away from said buff and said teeth being deformed radially into extended surface engagement with the deformed portions of said ring to secure said disk and ring to said buff, said teeth and said deformed portions of said ring extending axially beyond said ring to space said wheel from an adjacent wheel of a buffing assembly to form radial cooling air channels, and air directing fins struck from said disk and extending axially of said wheel at an acute angle thereto to underlie said buff, said vanes serving to direct air radially outwardly through channels defined by said teeth and said deformed portions of said ring spacing said wheel from an adjacent wheel into contact with said buff to cool the same and to prevent overheating thereof.

5. A buffing wheel comprising an annular cloth buff, a circular disk having portions struck therefrom along radially extending lines to provide air directing vanes lying at acute angles to the plane of the disk and air receiving openings through the disk, a ring and elements passing through said cloth buff to clamp the same between said disk and said ring outwardly of said air directing vanes and providing axially extending protuberances spacing said wheel from an adjacent wheel to provide spaces for the outward passage of air deflected by said vanes.
